UNITED STATES PATENT OFFICE

FRANK DITCHFIELD, OF CLEVELAND, OHIO, ASSIGNOR TO THE YOUNGSTOWN STEEL
DOOR COMPANY, OF CLEVELAND, OHIO, A CORPORATION OF OHIO

METAL DOOR CONSTRUCTION

Original application filed June 18, 1930, Serial No. 461,976. Divided and this application filed February 27, 1931. Serial No. 518,616.

This invention relates to improvements in metal door constructions, and the present application is a division of my co-pending application, Serial No. 461,976, for car construction, filed June 18, 1930.

In the manufacture and use of sheet metal doors, particularly adapted for railway house cars, the doors are generally made of three panels or sheets suitably rigidified by integrally formed indentations or corrugations and edge reinforcing elements. The dies required for corrugating or indenting the sheets are necessarily large and expensive. The sizes of door openings for box cars, automobile cars and the like vary in height for the cars of different railroads, thus necessitating corresponding variations for the over-all height of the doors used to close said openings.

Heretofore, to obtain different height doors with a plurality of corrugated panels, it has been customary to vary the width of the flat marginal portions used to form an ordinary plane overlapped joint. In carrying out such practice, it is evident that the spacing of the adjacent corrugations of the two overlapped panels will vary and hence the strength of the overlapped joint area will likewise vary. The greater the spacing between adjacent corrugations of two overlapped panels, the weaker the joint area and the more readily the panels may be bent or distorted, this weakness being accentuated as the total over-all height of the door is increased.

One object of my invention is to provide a joint between panels or sheets of a multiple panel sheet metal door such that the over-all height of the door may be varied within reasonable limits without the necessity of changing the dies for incorporating the strengthening corrugations or other indentations, which joint will retain the same strength regardless of the over-all height of the door.

More specifically, an object of my invention is to provide in a sheet metal door, particularly adapted for railway cars and having horizontal and vertical corrugations incorporated therein, a box girder joint be-

tween the adjacent secured horizontal margins of the several panels or sheets, which box girder formation increases in area in accordance with increases in over-all height of the door and vice versa so that the joint will preserve the necessary rigidity and strength, notwithstanding variations in the spacing of the adjacent horizontal corrugations of each pair of panels or sheets.

A still further object of the invention is to provide a joint as indicated in the preceding paragraph, which is obtainable without modification or changes in the dies and without added expense.

Other objects of the invention will more clearly appear from the description and claims hereinafter following.

In the drawings forming a part of this specification, Figure 1 is a front, elevational view of a portion of a side of a house car showing my improvements incorporated therein. Figure 2 is a vertical, sectional view, upon an enlarged scale, corresponding to the section line 2-2 of Figure 1, parts being broken out in order to better accommodate the figure on the sheet. Figure 3 is a horizontal, sectional view, upon an enlarged scale, corresponding to the section line 3-3 of Figure 1 and illustrating more particularly the construction at the front edge of the door. And Figure 4 is a view similar to Figure 3, corresponding to the section line 4-4 of Figure 1, and illustrating more particularly the construction at the rear edge of the door.

In said drawings, a portion of the side wall sheathing is indicated at 10, and the usual side door opening is shown as defined by side posts 11 and 12, lintel 13, and threshold plate 14. The lintel 13, as shown, constitutes a portion of the usual Z-bar side plate, to the outer depending flange of which is secured an upper guide 15 for the door, said guide 15 having a depending outer flange 16 received within U-shaped clips 17, secured to the top edge of the door, as shown in Figure 2.

Each of the posts 11 and 12 is of generally Z-section, with the outer flange thereof, however, turned back, as indicated at 18 and

19, respectively, the turned back flange 18 constituting one of the elements cooperating to provide the rear edge seal, as hereinafter described. To each of the posts 11 and 12 are secured the usual wood fillers 20—20 and the inner sheathing of the car is indicated at 21. The threshold 14 engages the edges of the floor boards 22, which are supported on the usual underframe, of which the channel side sill 23, only, is indicated in Figure 2. The door which I have chosen for illustration, is of the sheet metal type and preferably comprises three panels 24, 25 and 26, arranged horizontally one above the other and united along their horizontal adjacent edges in the manner hereinafter described.

The completed door is preferably formed with vertical edge corrugations 27 and 28, top horizontal corrugation 29 merging with the vertical corrugations, and a bottom horizontal corrugation 30, the latter being terminated inwardly of the vertical corrugations, so as to leave suitable flat spaces for securing of the roller brackets 31—31. Merging with the vertical corrugations 27 and 28 are a plurality of horizontally extending corrugations 32—32, a plurality of such corrugations being incorporated in each of the panels as shown.

The upper horizontal corrugation 29 is braced by a bridging strip 33 secured by riveting or welding to the panel sheet at points both above and below the corrugation, as shown best in Figure 2. The lower horizontal corrugation 30 is similarly braced by a bridging plate 34, as indicated in Figures 1 and 2, said plate being extended beyond the end of the corrugation 30 so as to provide a double ply opposite the roller brackets 31.

The vertical corrugations 27 and 28 are braced or rigidified by stiffeners 35, which fit within the panel corrugations, as best indicated in Figure 4, each of said stiffeners 35 being secured to the main panel sheets by rivets.

The front edge sealing arrangement for door is best shown in Figure 3. Secured to the multiple-ply flat marginal front edge of the door and extending the full height thereof, is a U-shaped sealing element 38, the opening or jaw of which faces toward the front door post. The depth of said element 38 will approximate the over-all thickness or depth of the door proper, as shown. Secured to the backturned flange 19 of the front door post 12 is a vertically extending, cooperable sealing element 39, of generally angular cross section, with one flange 40 thereof extending outwardly or normal to the plane of the car side. On the side of the flange 40 nearest the door and approximately midway thereof, is a vertically extending flange or rib 41 of tapered cross section, so located as to readily enter the

mouth or jaw of the door sealing element 38, when the door is in closed position. With this arrangement, it is evident that the element 39 functions as a stop for the front edge of the door and the cooperable elements 38 and 39 provide an effective weather seal, all as will more clearly appear by reference to my said co-pending application, Serial No. 461,976.

The rear edge seal for the door is provided by the backturned flange 18 of the rear door post and a sealing element 43 secured to the inner face of the multiple-ply rear marginal edge of the door. Said element 43 has a flange 44 which is extended inwardly and forwardly so as to enter behind the flange 18 and form a seal therewith, as will be evident from an inspection of Figure 4. To protect the sealing element 43 from injury and also to additionally strengthen or brace the vertical rear edge of the door, an angle 45 may be employed, the latter being secured to the door proper and element 43 by the same rivets 46 which secure the element 43. Said angle 45 has one of its flanges 47 extended inwardly across the edges of the sheets and beyond the rear edge of the element 43, and is preferably in engagement with the latter so as to act as a buffer when the door is opened against the usual door stops. With this construction, it will be apparent that the rivets 46 are placed under double shear, thereby adding greatly to the strength and preventing tearing out of the rivets or the sheet metal.

Referring next to the lap joints between the panels, as best illustrated in Figure 2, the upper panel of each pair will be slightly offset as indicated at 48, in an amount corresponding to the thickness or gauge of the sheet metal employed. Below the offset 48, the panel is extended vertically for a distance as indicated at 49 and is then bent outwardly and downwardly, as indicated at 50, and finally terminates in a wide flat flange 51 in a plane parallel to the main or original plane of the sheet, said flange 51 being flush with the tops of the several horizontal and vertical corrugations of the door. The upper portion of the lower of each adjacent pair of panels, has the uppermost horizontal corrugation thereof formed with a flat crest, as indicated at 52. The sheet is then bent inwardly and upwardly, as indicated at 53, and terminates in a wide vertical flange 54, in the original plane of the sheet, the upper edge of which is riveted to the offset portion 48—49 of the next upper panel, as by rivets 55—55. The lower edge of the outwardly offset flange 51 of the upper panel is riveted, as indicated at 56, to the flat crest of the corrugation 52. In this connection, it will be understood that, near the vertical edges of the door, the upper portion of each of the panels 25 and 26 will be

conformed to fit the vertical corrugations, as indicated at 57—57 in Figures 3 and 4.

With the form of lap joint for the panels, above described, it is evident that a box girder construction is obtained of parallelogram vertical cross section, which provides great strength against collapse or bending in any direction. Another important result flowing from the improved box girder construction is that a considerable variation in the over-all height of the three secured panels is obtainable, without change of dies. By varying the width of the flanges 51 and 54 at each joint, which can be done without changing or adjusting the dies that form the corrugations and the offsets 49, 50 and 51, the size of the box girder formation may be varied, as will be understood.

Heretofore, with the ordinary type of plane lapped joint in the original plane of the sheets, increases in the width of the marginal portions of the panels which are lapped, obviously increase the distance between those horizontal corrugations immediately above and below the joint, thereby weakening the door at this area, whereas as due to the box girder formation herein described, variations in the width of the flanges 51 and 54 does not affect the strength of the joint. The less the over-all height of the door, the nearer together are the inclined sections 50—53 of the joint with a consequently smaller section modulus for the girder section and, as the over-all height is increased, the farther apart are the inclined sections 50 and 53 with a corresponding increase in section modulus for the girder formation.

As shown, the door is of the bottom hung type, each of the rollers 58 riding on a track 59, which is secured, at intervals, to supporting brackets 60 riveted to the side sill 23. To prevent the lower edge of the door swinging out, each of the roller brackets 31 is preferably provided with hook formations 61, engaging beneath the depending outer flange 62 of the track, as best shown in Figure 2.

To provide an effective weather seal for the bottom edge of the door, the following arrangement is employed. The threshold plate 14 (see Figure 2) is extended around the floor boards 22, as indicated at 63 and is then extended horizontally inwardly, as indicated at 64, thence vertically downward, as indicated at 65, thence horizontally outward, as indicated at 66, and finally to the depending vertical flange 67, by which it is secured to the bracket 60, preferably by the same rivets which attach the track 59. As will be evident, the longitudinally extending sections 64, 65 and 66 form a horizontally extending channel or groove opening horizontally outwardly, the upper wall 64 of which is disposed flush

with the lower edge proper 68 of the door. Said channel provides an air pocket extending the full width of the door when in closed position, so that, when any rain, sleet or other foreign matter is driven horizontally below the edge of the door into said channel or pocket, the momentum of said rain, snow, sleet or the like will be immediately destroyed and the same will fall down by gravity onto the lower wall 66 of the channel and then drain off, as will be evident, and all as more fully described in my said application, Serial No. 461,976.

I have herein shown and described what I now consider the preferred manner of carrying out my invention, but the same is merely illustrative and I contemplate all changes and modifications that come within the scope of the claims appended hereto.

I claim:

1. In a door of the class including a plurality of sheet metal panels with the main portions thereof located in substantially the same plane and each panel having strengthening indentations incorporated therein; means for uniting the panels along adjacent edges, said means including: a flange on one panel offset to one side of the main plane of said panel, and an offset to the same side on the adjacent panel located inwardly from the edge of the last named panel, the flange of the first named panel being secured to said offset of the second named panel and the edge of the second named panel beyond said offset thereof being secured to the main portion of said first named panel whereby to provide a box girder lap joint between the panels.

2. In a door of the class including a plurality of sheet metal panels disposed one above the other with the main portions thereof located in substantially the same plane and having horizontally extending corrugations incorporated in the panels; means for uniting the panels along their adjacent edges, said means including an offset flange on one of the panels secured to the adjacent horizontal corrugation of the next panel, the latter having its marginal portion outwardly of said horizontal corrugation secured to the first named panel whereby to provide a box girder joint.

3. As an article of manufacture, a door comprised of a plurality of sheet metal panels arranged one above the other and united along their adjacent horizontal edges, each of said panels having horizontally extending corrugations formed therein, the upper of two adjacent panels having its lowermost portion, below the lowermost corrugation therein, extended first outwardly and then downwardly in a plane parallel to but offset from the main plane of the panel, said downwardly extended portion being secured

to the crest of the uppermost horizontal corrugation in the lower of the two panels, the lower of the two panels having its upper portion, above its uppermost horizontal corrugation, extended upwardly and secured to the upper of the two panels above the outwardly offset portion thereof, whereby to form a box girder joint the cross section modulus of which may be proportioned to the distance between the horizontal corrugations of the two panels on opposite sides of the box girder.

4. The herein described improvement in doors constructed in part of sheet metal panels having corrugations therein parallel to the joint between the panels and wherein the corrugations are all offset to the same side of the main plane of the panel sheets, comprising: an edge portion of one panel sheet extended first outwardly from the main plane of the panel sheet to the same side as the corrugations therein and then extending in a flat marginal portion parallel to the main plane of the sheet; a flat marginal portion on the adjacent panel sheet in substantially the same plane as the main portion of said sheet and disposed outwardly beyond the adjacent corrugation therein; means rigidly uniting said marginal portion of the second named sheet and the first named panel sheet in substantially the main plane of the latter; and means rigidly uniting the edge of the first named panel sheet to the crest of said corrugation of the second named panel sheet, whereby, the cross section modulus of the box girder joint thereby formed may be varied to correspond with the distance between the adjacent corrugations of the two panels by varying the width of said marginal portions.

In witness that I claim the foregoing I have hereunto subscribed my name this 23rd day of February, 1931.

FRANK DITCHFIELD.
